COMBINED PORTABLE BEACH CHAIR AND UMBRELLA THEREFOR

William W. Peery, 6649 Van Gorden Court,
Arvada, Colo. 80002

Filed Aug. 6, 1969, Ser. No. 18,553

Term of patent 14 years

Int. Cl. D6—01

U.S. Cl. D15—8

FIG. 2

FIG. 3

Des. 219,377

PAGE 4

FIG. 4

FIG. 5

FIG. 6

FIG. 1 is a front isometric view of a combined portable beach chair and umbrella therefor embodying my new design, with the chair in an unfolded position.

FIG. 2 is a rear isometric view of the combined portable beach chair and umbrella therefor shown in FIG. 1.

FIG. 3 is a front isometric view of the combined portable beach chair and umbrella therefor embodying my new design in a compact folded position for carrying.

FIG. 4 is a rear isometric view of the combined portable beach chair and umbrella therefor shown in FIG. 3.

FIG. 5 is an isometric view of a combined portable beach chair and umbrella therefor embodying my new design in a partially folded position.

FIG. 6 is an isometric view of a combined portable beach chair and umbrella therefor embodying my new design in a partially unfolded position.

FIG. 7 is a section view taken substantially in the plane of line 6-6 on FIG. 5, but with chair partially unfolded.

I claim:

The ornamental design for a combined portable beach chair and umbrella therefor, as shown.
